BURNER

Ralph Hageman, Cedar Rapids, Iowa, assignor to
 Johnson Gas Appliance Company, Cedar
 Rapids, Iowa, a corporation of Iowa

Application December 31, 1934, Serial No. 759,885

1 Claim. (Cl. 158—117.1)

This invention relates to burners and has particular relation to a burner head and control mechanisms for such burners.

In providing gas burners for house heating and the like, it is becoming increasingly important that the burners themselves be extremely simple and sturdy in construction and that they be provided with dependable safety control systems for preventing the escape of unburned gas from the burner when it is ignited.

The devices known to the art are not entirely satisfactory in meeting the requirements and it is accordingly a general object of my invention to provide an improved burner and control systems for such a burner.

A more specific object of my invention is to provide a highly efficient burner head which does not require a primary air supply.

Another object of my invention is to provide a simple, reliable and efficient thermostatic control for a burner head which will prevent the discharge of gas from a burner head unless the pilot burner is ignited.

Other and further features and objects of my invention will be more apparent to those skilled in the art upon a consideration of the accompanying drawing and following specification, wherein is disclosed an exemplary embodiment of the invention, with the understanding, however, that such changes may be made therein as fall within the scope of the appended claim without departing from the spirit of the invention. The device may be used or adapted for use for other purposes.

In said drawing:

Figure 1 is a view in perspective of a burner constructed according to one embodiment of my invention; and

Figure 2 is a view, partly in section and partly in elevation, of the burner shown in Figure 1.

Referring now to the drawing:

The main body or barrel of the burner, indicated at 10, is a substantially cylindrical member having a substantially rectangular boss 11 at one side thereof. The burner body is chambered to provide an inlet chamber 12 and a burner head chamber 13. This division of the interior of the burner barrel 10 is accomplished by means of a partition which projects outwardly from the lower inside wall of the barrel in a semi-circular form as indicated at 14a, then upward in a rectangular portion 14b extending, of course, from wall to wall and then to the other side of the inner wall of the barrel as indicated at 14c.

Gas is let into the barrel 10 through the tapped

opening 16 and passes from the chamber 12 into the chamber 13 through an opening 17 in the wall 14b, the flow of gas from one chamber to the other being controlled by means of a valve 18 as is hereinlater more particularly described.

The upper end of the barrel 10 is provided with an upwardly projecting collar 21 which is threaded on its outer wall as indicated at 22 and which has an opening 23 therethrough leading from the chamber 13 into the "mushroom" burner head 24.

The peculiarly shaped "mushroom" or "door knob" head is not accidental but has been so devised that this burner will burn with a highly efficient flame without the necessity of furnished "primary" air to the burner. This is of particular importance in this type of burner.

Whereas most burners known to the art require primary air in order to obtain an efficient heating flame from the burner, this peculiarly shaped head and the position, size and number of burner openings permit the elimination of and avoid the necessity for supplying primary air to the burner. The chamber 26 within the mushroom head and the channel leading into the chamber from the barrel 10 preferably follow the contour of the head 24. Any suitable arrangement and disposition of burner openings may be employed, but I have found that a very desirable arrangement is to provide some twenty-four openings in circular arrangement around the periphery of the head where the slope of the head is almost vertical. The openings are preferably drilled in a horizontal plane which is substantially perpendicular to the surface and I have found that about twenty-four openings equally spaced about the circle and of about number forty-seven diameter provides a highly efficient heating flame which will be at least a ninety per cent blue flame. I attribute the fact that this burner does not need a primary air supply to the peculiar shape of the head and the arrangement, disposition, size and number of the burner openings. I have found other shapes and arrangements of burner openings to operate with reasonable efficiency. For instance, conical or frusto-conical shapes of burner heads have been employed with reasonable success. The present shape and arrangement, however, has been found to be about the most efficient of all the shapes and arrangements tested. The location, number and size of openings in the head is of secondary importance to the shape of the head and other openings have been employed with varying success.

Burners of this type, since they are ordinarily

intermittently operated, are usually adapted to be ignited by means of a pilot burner such as the burner indicated generally at 31. In order to provide a compact and solid unit I preferably 5 mount the pilot burner on an enlarged portion 11a of the boss 11, which boss is preferably integrally cast with the barrel 10. In the present instance the pilot burner is comprised of a highly porous ceramic tip 32 which is mounted upon a 10 thimble 33 which is, in turn, mounted on a short nipple 34. The short nipple 34 is threaded into a suitable opening 36a in the rectangular boss 11a. Another tapped opening 36 is drilled in the boss to conduct gas from a supply pipe (not 15 shown) to the pilot burner.

As a safety device, to prevent gas from being admitted to the main burner if the pilot burner is not ignited, I preferably mount a bi-metallic control element 41 on the boss 11a in such a 20 position that the bi-metallic strip 42 is adjacent to the flame produced by gas issuing from the pilot burner 31. The bi-metallic element 41 is preferably comprised of a rigid strap 43 which is fastened in upright position in a suitable slot 44 25 in the boss 11a by means of a bolt 46. The bi-metallic strip 42 is preferably bent in a roughly inverted U-shape as shown on the drawing and is fastened to the strap 43 as by means of rivets 47. An operating lever arm 48 is fastened to the other 30 end of the bi-metallic strip 42 as by means of rivets 49 and this lever arm extends downwardly substantially parallel to the strap 43 to a position below the plane of the boss 11a. The lever arm 48 is provided with a slot 51 at its lower end and 35 the slot 51 is adapted to engage a circular recess 52 in a coupling member or sleeve 53. The coupling member 53 is threaded on the projecting end of the stem 18a of the valve 18.

The neck 25 of the burner head 24 is threaded 40 onto the upper end of the barrel 10 and the barrel 10 is provided with flat surfaces 30 at the upper end thereof to provide a nut flange to permit the barrel to be threaded onto a supply conduit such as the pipe 35. The plug 40 is 45 threaded into the side wall of the barrel 10 opposite site to the valve 18 in order to permit removal of the valve.

It is obvious, from inspection of the drawing, 50 that when the pilot burner 32 is ignited the heat from the flame will strike the bi-metallic strip 42 and, since the outermost layer of the bi-metallic strip is of a material having a higher coefficient of expansion than the innermost por-

tion of the strip, the lever 48 will be moved inwardly toward the barrel 10 to raise the valve 18 from its seat and permit gas to flow from the chamber 12 into the chamber 13 when the main control valve (not shown) is opened. If the main 5 control valve (not shown) is opened and the pilot burner is not ignited the valve 18 will remain closed and gas cannot enter the chamber 13, thus preventing the escape of unburned gas from the burner. It is to be observed that the non-operative 10 position of a thermostat is the "off" position.

Of course, if the pilot flame is not ignited, a certain amount of unburned gas escapes into the furnace and up the stack but tests have proven that this amount of gas is only in the neighborhood of one cubic foot per hour and that a leakage of this kind only becomes dangerous when the volume is in the neighborhood of ten cubic feet per hour.

Although I have described a specific embodiment of my invention it is apparent that modifications may be made by those skilled in the art. Such modifications may be made without departing from the spirit and scope of my invention as set forth in the appended claim.

I claim as my invention:

A gas burner comprising a substantially cylindrical, vertically-extending casing, a main burner element associated with the upper end of the casing, a boss extending laterally from the side of said casing at a point intermediate its ends, a vertical partition within said casing extending transversely thereof and forming on the opposite sides thereof a gas inlet chamber and a gas outlet chamber, said partition being provided with a port, a valve for closing said port, a valve rod extending laterally through said outlet chamber and from said casing parallel to and in the direction of said boss, a pilot burner secured to the top face of said boss at a point inwards of the free end of the boss, a bi-metallic thermostat secured at one end to the free end of said boss and being formed into an inverted U-shape, said pilot burner extending upwardly between said casing and said thermostat to a point adjacent the burner element, the free end of the thermostat being connected to the outer free end of the valve rod, said free end being movable, when the thermostat is heated by the pilot burner, towards said casing to move said valve and rod to unseat said valve whereby to admit gas to said gas outlet chamber.

RALPH HAGEMAN.
